(57) **CLAIM**

I claim the ornamental design for a Hood Latch as shown and described.

DESCRIPTION

FIG. 1 is a Perspective view of a hood latch showing my new design;

FIG. 2 is a Front view thereof;

FIG. 3 is a Back view thereof;

FIG. 4 is a Left-side view thereof;

FIG. 5 is a Right-side view thereof;

FIG. 6 is a Top view thereof; and

FIG. 7 is a Bottom view thereof.

The broken lines in the drawings depict portions of the Hood Latch that form no part of the claimed design.
